UNITED STATES PATENT OFFICE.

WALTER E. BANNING, OF SYRACUSE, NEW YORK.

DESIGN FOR A NUMBER-PLATE.

SPECIFICATION forming part of Design No. 25,829, dated July 21, 1896.

Application filed June 3, 1896. Serial No. 594,178. Term of patent 3½ years.

To all whom it may concern:

Be it known that I, WALTER E. BANNING, a citizen of the United States, residing at Syracuse, in the county of Onondaga and State of New York, have invented and produced a new and original Design for a Pattern for Bicycle-License-Number Plates; and I do hereby declare the following to be a full, clear, and exact description of the same, reference being had to the accompanying drawings, forming a part thereof.

Figure 1 is a plan view of a pattern for a bicycle-license-number plate, showing my design; and Fig. 2, an edge view, said views fully illustrating my design.

The leading feature of my design consists in a flat field partially bounded by segment-shaped or particircular outlines located at diametrically opposite edges of the field, and 20 lineally-elongated prolongations or capes of the field located diametrically opposite each other and at a right angle to the direction of projection of the particircular boundary portions, the lateral outlines of said capes being 25 slightly convergent outwardly and respectively terminated by an end outline of segmental contour, while contiguous the capes' extremities are respectively small and open circular outlines.

Referring to the drawings, A is the central 30 or main portion of the flat field, terminated at opposite sides by parti or semi circular edges *a a*; B B, the oppositely lineal protruding capes or prolongations, bounded, respectively, by brief curved outlines *b b*, continuing from the 35 outlines *a a* and ending in the straight and slightly-converging outlines *c c*, outwardly terminated by the uniting outline *d*; and contiguous the extremity of each cape extension of the main center field A there is an open 40 circular outline *e* of small diameter.

The thickness of the pattern is slight, and the obverse and reverse fields are parallel, and, as obvious, coinciding in the outlines 45 bounding them.

As is apparent, my design is such as to be thoroughly harmonizing, and yet distinctive.

What I claim is—

The design for a pattern for a bicycle-license-number plate, substantially as shown 50 and described.

In testimony whereof I affix my signature, in presence of two witnesses, this 12th day of December, 1895.

WALTER E. BANNING. [L. s.]
